SPORTS HELMET

Malcolm F. Cox, Mississauga, Ontario, Canada, assignor to Canada Cycle & Motor Company Limited, Weston,
Ontario, Canada

Filed July 30, 1975, Ser. No. 600,233

Claims priority, application Canada Mar. 24, 1975

Term of patent 14 years

Int. Cl. D2—03

U.S. Cl. D2—231

FIG. 1

FIG. 2

FIG. 3

FIG. 5

FIG. 4

FIG. 1 is a perspective view of a sports helmet from the front and one side, viewed from below showing my new design;

FIG. 2 is a perspective view corresponding to FIG. 1 from the rear and the opposite side, viewed from above;

FIG. 3 is the side view of the design; and FIGS. 4 and 5 are front and rear views respectively of the design.

I claim:
The ornamental design for a sports helmet, as shown.
